JOINT HOLDER AND EDGING UNIT

Robert R. Robertson, Chicago, Ill., assignor to
 The Translode Joint Company, Chicago, Ill.,
 a corporation of Illinois

Application November 14, 1935. Serial No. 49,695

21 Claims. (Cl. 94—51)

In the construction of concrete roads and the like, it has been the practice to provide expansion joints at spaced intervals, said joints being formed by means of expansion joint forming mechanisms, parts of which are left in the concrete, and other parts of which are removed after the pouring of the concrete. During the pouring of the concrete, difficulties have been encountered in holding the expansion joint forming mechanisms in their proper positions on the road subgrade, due to the fact that as the concrete is poured and pushed into position, the expansion joint mechanisms have either been pushed out of place or tipped over, thereby requiring replacement of the joint forming mechanisms and repositioning of the same, causing loss of time and additional expense.

The present invention has been devised to obviate the difficulties hereinbefore encountered in holding expansion joint forming mechanisms in position during the pouring of concrete. The present invention relates more particularly to a combination expansion joint holder and edging unit for use in connection with a load transmission expansion joint forming mechanism, including a precast plastic core or filler having an asphalt top seal or head secured across the top thereof into which the tapered pins of a steel edging bar are adapted to be pressed, after which the edging bar is enclosed by means of a protecting hood or cap forming part of the joint holding mechanisms, which are removable before the last pass of the road finishing machine to permit proper rounding or edging of the upper edges of the concrete slabs and removal of the edging bar and pins after the initial set of the concrete.

It is an object of this invention to provide an improved removable joint holder for holding an expansion joint forming unit in position during the pouring of concrete in the formation of a road or the like.

It is also an object of this invention to provide a narrow removable edging unit for removable engagement on the upper surface of a plastic joint filler, and beneath a protecting cap forming part of a joint holder used for holding the joint forming mechanism in position during the pouring of concrete, and removable from the concrete while it is still soft, thereby exposing the edging unit to permit rounding or edging of the upper corners of the concrete slabs, allowing the edging unit to be removed after the initial set of the concrete to provide a void above the plastic filler forming the joint for the reception of a compound filler for filling the top of the finished joint.

It is a further object of this invention to provide a removable narrow edging unit for positioning upon the top of a transload joint forming mechanism to provide a narrow crack between the adjacent upper portions of concrete road slabs above the expansion joint mechanisms to be filled with a compound filler to form a plastic closure for the top of the joint, which is comparatively narrow when compared with the width of the expansion joint mechanisms separating the road slabs beneath the top filler.

It is furthermore an object of this invention to provide a load transmission expansion joint unit including a plastic core provided with a metal cross plate or a wide plastic head or a combination of the two, upon which a narrow edging unit is removably supported and covered by means of a cap forming a part of a holding mechanism for bracing the expansion joint forming mechanisms and the cap in position during the pouring of concrete, said holding mechanism including removable stake pins projecting through apertured bracket arms, and adapted to be driven into the subgrade to brace the joint forming mechanisms against the advance of concrete poured on the opposite sides of the joint by means of concrete pouring and finishing machines.

It is an important object of this invention to provide a joint holder and edging unit for use in the construction of concrete roads and the like, with said holder formed to permit the same to be removed before the last pass of the concrete finishing machine, to uncover a narrow edging unit releasably supported on the top of the expansion joint filler core to permit rounding or edging of the upper edges of adjacent concrete slabs, to form a narrow crack for the reception of a compound filler above the plastic filler core of an expansion joint formed between the concrete road slabs.

Other and further important objects of this invention will be apparent from the disclosures in the specification and the accompanying drawings.

The invention (in a preferred form) is illustrated in the drawings and hereinafter more fully described.

On the drawings:

Figure 1 is a fragmentary top plan view of a load transmission expansion joint forming mechanism including a removable edging unit and a removable holder embodying the principles of this invention.

Figure 2 is an enlarged fragmentary vertical

section taken on line II—II of Figure 1, showing the concrete road slabs in position for embedding the expansion joint mechanisms and the edging and holding units before the last pass of the finishing machine, and while the concrete is still soft to permit removal of the joint holder.

Figure 3 is a similar fragmentary cross section of the expansion joint illustrated in Figure 2 after the removal of the joint holder, but with the edging unit still in position upon the top of the joint filler to facilitate edging of the upper edges of the concrete slabs, prior to the initial set of the concrete when the edging unit is removed to provide a narrow crack above the expansion joint filler and between the upper portions of the adjacent road slabs.

Figure 4 is a fragmentary vertical section through the upper portion of the finished expansion joint after the removal of the edging unit, and after a compound filler has been poured into the narrow top crack of the joint above the wide head of the main filler forming part of the expansion joint.

Figure 5 is a fragmentary vertical section similar to that illustrated in Figure 2 of the upper portion of a modified form of core unit provided with a metal plate cross head between the plastic core and the metal edging unit.

Figure 6 is a fragmentary isometric view of the metal cross head plate, of the type shown in Figure 5, removed from the joint.

Figure 7 is a fragmentary vertical section through the upper portion of an expansion joint core and edging unit having engaged therebetween another modified form of a metal cross head for a joint.

Figure 8 is a fragmentary isometric view of the upper portion of the core and metal cross head illustrated in Figure 7 showing the wedging pins in section.

Figure 9 is an enlarged fragmentary isometric sectional view of another modified form of expansion joint forming mechanism wherein a grooved metal cross head plate is engaged between the top of the plastic core and a plastic cross head on which the edging unit is supported.

Figure 10 is a fragmentary isometric sectional view of another modified form of expansion joint forming mechanism in which another modified form of a cap type metal cross head is engaged on the top of the joint forming core for the support of the edging unit.

As shown on the drawings:

The present invention relates to an improved road expansion joint forming mechanism, of the load transmission type, and includes a removable edging unit and a joint holder serving the double purpose of enclosing the edging unit during the pouring of concrete, and also acting as a brace for supporting the expansion joint forming mechanism in place during the pouring of the concrete to form road slabs on opposite sides of the joint.

In the present showing, the reference numeral 1 indicates a road subgrade upon which concrete is deposited to form the concrete road slabs 2 separated from one another by means of the improved load transmission expansion joint and mechanism. The improved metal edging unit 16 and the joint holder form subcombinations of the joint forming mechanisms, which include in combination a load transmission base unit which carries a filler or core unit upon which the edging unit is supported and which is braced in position by the joint holder. In the present show-

ing, the base unit of the joint comprises an elongated base member consisting of a solid base plate 3 constructed of sheet metal or other suitable material. The longitudinal margins of the base plate 3 are bent upwardly and then inwardly toward one another to form oppositely positioned guide channels 4. The guide channels 4 of the base unit provide oppositely positioned guide grooves 5. The margins of the top plates of the guide channels 4 are bent upwardly and are cut away to provide spaced upwardly projecting retaining flanges 6, which are arranged in staggered relation on opposite sides of the base unit. Notches are provided between the retaining flanges 6 on each side of the base unit to permit load transmitting anchor shoes or holders to be seated therein in proper spaced relation for the support of a core unit or filler hereinafter more fully described.

The load transmitting devices associated with the base unit consist of a plurality of anchor shoes or holders, which are movably or shiftably engaged in the base section and are arranged longitudinally in offset or staggered relation with respect to one another. The anchor shoes or holders are of substantially identical construction and are arranged with the adjacent shoes reversed with respect to one another, as clearly illustrated in Figure 2. Each of the anchor shoes is constructed of metal and comprises an angle bar including a base flange 7 and an upright flange or web 8 integral with the base flange. Struck outwardly from the upper margin of each of the upright flanges or webs 8 are anchoring blades or wings 9 leaving the inner side of the upright flange or web flat.

Supported on the base flanges 7 of the anchor shoes between the upright flanges or webs 8 is a pre-molded asphalt filler or core board 10 having staggered rows of bosses or knobs 11 and sockets or recesses 12 formed on each side thereof. Seated upon the top edge of the plastic filler 10, and secured thereto by means of nails is a top seal in the form of a plastic filler head 13 constructed of asphalt or a similar material. Metal core plates 14 are provided on opposite sides of the filler 10 in contact with the outer surfaces of the knobs or bosses 11. The plates 14 project down into the base unit adjacent the inner faces of the upright flanges 8 of the anchor shoes. The upper margins of the plates 14 are bent into the form of angle strips 15 which seat against the lower side corners of the filler cross-head 13 to close the top of the filler chamber in which the core or filler 10 is disposed.

Disposed longitudinally upon the filler head 13 midway between the sides thereof is a removable steel edging bar 16 having rigidly secured in spaced openings in the bottom surface thereof of a row of tapered pins or pegs 17 which are adapted to be pressed or forced into the plastic filler head 13 by pushing the edging bar into position upon the top surface of the head 13 as illustrated in Figure 2. The edging bar 16 is removable for reuse and as clearly illustrated in Figures 2 and 3 is comparatively narrow in order to provide a narrow top groove or crack 18 between the upper portions of the concrete slabs 1.

During the pouring of the concrete, the edging bar 16 is inclosed by means of a long hood or cap 19 of substantially horseshoe shaped cross-section as shown in Figure 2. The channel cap 19 when in use is positioned with the open bottom thereof seated upon the top surface of the filler head 13 and forms part of a joint holder which

is used for the purpose of securely bracing the joint forming mechanisms in position during the pouring of concrete. The joint holder includes the channel cap 19 which has secured to one side 5 thereof a plurality of spaced angle brackets 20 each of which is provided with an opening or hole near the outer end thereof. Welded or otherwise secured to the bottom of each of the angle brackets 20 is an inclined brace or sup- 10 porting leg 21 of a length sufficient to permit the lower end to rest upon the top of one of the guide channels 4 forming part of the load transmission base unit. Also welded or otherwise secured to the bottom of each of the angle brackets 15 20 is an angle stop bracket 22, one flange of which projects downwardly to serve as a stop for engagement against one side of the filler head 13.

Removably projecting downwardly through the 20 opening in each of the angle brackets 20 is an anchoring stake 23, the lower end of which is provided with a tapered tip 24 to permit the stake to be driven into the subgrade 1. Secured in the upper end of each of the stakes 23 is an out- 25 wardly projecting arm or handle 25 to facilitate removal of the stakes after the pouring of concrete and before the last pass of the finishing machine. The handles 25 also prevent the stakes 23 from being driven through the brackets 20.

30 After the expansion joint forming mechanisms are positioned upon the subgrade as illustrated in Figure 2 and the stakes 23 are driven into the subgrade to hold the joint forming mechanisms braced in position on the side opposite the side 35 against which the concrete is adapted to be deposited by a concrete machine, concrete is deposited by the concrete furnishing machine and as the machine advances toward the joint forming mechanisms the concrete is pushed into position 40 and over the top of the joint into the space on the opposite side of the joint where the joint holder is positioned. The joint holder acts to brace the joint forming mechanisms in position and also serves to hold the cap upon the top of 45 the filler head 13 to inclose the edging bar 16. After the concrete has been poured to embed the joint forming mechanisms including the cap 19 and the joint holder, the stakes 23 are removed by means of the handles 25 and the main 50 portion of the joint holder is pulled upwardly out of the soft concrete together with the cap 19. The removal of the cap 19 and the joint holder is done before the last pass of the concrete finishing machine.

55 With the removal of the cap 19 and the joint holder, the concrete which is still soft fills the voids left by removal of the cap 19 and the joint holder. The removal of the cap 19 exposes the edging bar 16 to permit the soft concrete to 60 extrude against the opposite sides of said bar. After the initial set of the concrete, the upper corners of the concrete slabs 1 on opposite sides of the bar 16 are edged or rounded as illustrated in Figure 3. When the edging is completed, the 65 edging bar 16 together with the pins 17 is pulled upwardly out of engagement with the filler head 13 to leave a narrow crack or groove 18 between the top portions of the concrete slabs above the top seal or head 13 of the joint. The top groove 70 or crack 18 is now filled to a point near the top surface of the concrete, with a compound filler, such as tar or the like, to form a narrow plastic filler or top rib 26 to seal the top of the joint above the top seal or head 13.

75 The removed edging bar 16 and the joint holder

are adapted to be repeatedly reused for the purpose of securely bracing load transmission expansion joint forming mechanisms in position during the pouring of concrete, with the edging bar 16 inclosed by the cap 19 during the pouring of concrete and later on serving as a means for edging the upper corners of the concrete slabs and for forming a narrow top crack or groove above the joint for the reception of a compound filler to seal the top of the joint.

In the modified form of the device illustrated in Figures 5 and 6, the parts which are identical with those illustrated in Figures 1 to 4 inclusive are designated with like numerals. In this modified form of the filler mechanism, the reference numeral 26 indicates a precast plastic core board, the lower edge of which is adapted to be seated in a load transmission base similar to the type illustrated in Figure 2, or if preferred the plastic core board may be seated upon any other suitable type of joint forming base. Seated upon the top surface of the plastic core board 26 is a metal crosshead consisting of two overlapping metal plates 27 the outer margins of which are bent downwardly and inwardly to form stiffening beads or hems 28. The cross-head plates 27 are provided with openings 29 in the overlapping margins thereof to permit the pins 17 of the edging bar 16 to be projected downwardly through said openings into the plastic filler board 26. The metal crosshead plates 27 are preferably formed of rolled copper and are provided with a series of openings 30 adjacent the rolled margins thereof as clearly illustrated in Figure 6. The openings 30 are adapted to be filled with concrete and together with the rolled margins 28 of said copper plates serve as a means for anchoring the plates in the opposite concrete road slabs 2. The upper portion of the joint is adapted to be completed after the removal of the cap 19 and the holder mechanism and after the edging bar 16 together with the pins 17 have been removed to leave the narrow space at the top of the joint to be filled with a compound filler similar to the arrangement illustrated in Figure 4.

Figures 7 and 8 illustrate another modified form of expansion joint core unit comprising a precast asphalt core board 31 provided with a central top groove 32 which extends throughout the entire length of the core board. Seated upon the top of the plastic core board 31 is a metal crosshead or upper joint seal comprising two rolled copper plates 33 the outer longitudinal edges of which are rolled downwardly to provide reinforcing feet or margins 34 while the inner longitudinal margins of the copper plates 33 are deflected downwardly to form flanges 35 which project downwardly into the top middle groove 32 of the core board 31. The copper plates 33 are provided with openings 36 for the reception of concrete to assist in anchoring the plates 33 in the concrete road slabs 2. Seated upon the top of the copper plates 33 is a steel edging bar 16 provided with downwardly projecting pins 17 which wedgingly project downwardly between the flanges 35 of the copper plates 33 and into the plastic material forming the core board 31.

Figure 9 illustrates another modified form of an expansion joint former comprising a precast asphalt core board 37 provided with a longitudinally disposed middle top groove at 38. Seated upon the top of the core board 37 is a copper crosshead plate 39, the margins of which

65

70

75

are rolled over to form reinforcing rims or beads 46. The margins of the plate 39 are provided with concrete receiving apertures 41. The central portion of the plate 39 is deflected to form a depressed channel 42 which seats in the groove 38 formed in the top of the plastic board 37. Seated upon the top of the copper plate 39 is a precast asphalt top seal or crosshead bar 43 which is adapted to be secured in place by means 10 of nails 44 or other suitable means which are driven downwardly through the bar and the copper plate 39 and into the core board 37. The pins 47 of the edging bar are adapted to be driven or forced downwardly into the plastic 15 crosshead bar 43 to removably hold the edging bar 16 in position.

Figure 10 illustrates another modified form of an expansion joint forming unit including in combination a precast asphalt core board 10 similar to the core board illustrated in Figures 20 1 to 4 inclusive, having metal core plates 45 positioned on opposite sides thereof in contact with the bosses 11. Seated upon the top of the core board 10 is a copper crosshead plate 46 25 the middle portion of which is formed to provide a channel 47 which fits over the upper portion of the core board. The outer margins of the copper crosshead plate 46 are turned downwardly and inwardly to form reinforcing ribs or 30 margins 48. The top of the channel portion 47 of the crosshead member is provided with spaced apertures for the reception of the pins 47 of a steel edging bar 16.

The various forms of expansion void forming 35 mechanisms illustrated in Figures 5 to 10 inclusive are adapted to be used in combination with a load transmission plate mechanism similar to that illustrated in Figures 2 and 3 or with any other suitable type of joint forming base 40 which will close the bottom of the expansion joint.

In actual practice the base unit with the core 45 forming mechanism seated thereon and having the removable metal edging bars mounted in place are assembled and are wired or secured together before being shipped to location so that the assembled mechanisms may be readily positioned in place upon a road sub-grade ready to be embedded in concrete. The bracing units for 50 the joint forming mechanism are shipped separately and are adapted to be readily engaged in position with the cap 19 disposed over the edging bar after which the stakes 23 are driven into the subgrade as illustrated in Figure 2 to hold the joint forming mechanism properly 55 braced in position to permit the pouring of concrete without disturbing the position of the joint forming mechanism.

It will of course be understood that various 60 details of construction may be varied through a wide range without departing from the principles of this invention and it is therefore not the purpose to limit the patent granted hereon otherwise than necessitated by the scope of the 65 appended claims.

I claim as my invention:

1. In a joint forming mechanism for embedding 70 between concrete sections of a road the combination with an expansion joint base, of a preformed core supported thereon and including a top seal head, plates secured on opposite sides of the plastic filler and supported by said base with the tops of said plates formed to seat around the bottom corners of the top seal head, an 75 edging bar including pins to be driven into the

top seal head to hold the edging bar removably secured in place upon the top seal head, and a joint holder for bracing the joint forming mechanism in place and including a cap for enclosing the edging bar, apertured brackets secured to the cap, legs secured to the apertured brackets and braced against the base, stop members on the brackets engaged against the top seal head, stakes projecting through the apertured brackets and driven into the road 10 subgrade to hold the joint forming mechanism braced in position during the pouring of concrete, and handles on the stakes for removing the same and the joint holder after the pouring of concrete. 15

2. In a road joint forming mechanism for embedding between concrete road slabs upon the road subgrade the combination of an expansion joint base, of a precast filler supported thereon, a preformed top seal head of plastic material 20 seated upon the top of the filler, plates supported on the base and engaged against opposite sides of the filler and said top seal head, an edging bar including stakes which are driven into the top seal head for holding the edging bar removably secured in position, a joint holder positioned against one side of the base and the filler and including a cap for inclosing the removable edging bar, and means for securing the joint holder in position to brace the joint forming mechanisms including the joint holder cap in position during the pouring of concrete for the formation 25 of the road slabs between which the joint is formed. 30

3. In an expansion joint forming mechanism 35 including a preformed plastic filler, the combination of an edging bar including pins driven into the plastic filler for holding the edging bar in place, a joint holder including a cap removably engaged on the top of the plastic filler for 40 enclosing the edging bar, bracket means for holding the cap in position, and securing stakes engaged with the bracket means and releasably driven into the road subgrade for bracing the joint forming mechanism in position during the 45 pouring of concrete to form road slabs.

4. The combination with a concrete road expansion joint forming mechanism including a preformed plastic filler, of a metal edging bar, of less thickness than the filler and seated on 50 edge thereon leaving strips of the top of the filler exposed to be covered by concrete and pins secured in the edging bar and driven into the precast filler for releasably holding the edging bar in position to permit edging of the concrete slabs 55 forming part of the concrete road after the initial set of the concrete and before the removal of the edging bar and the pins to form a narrow crack above the precast filler for the purpose of receiving a top filling to seal the top of the joint. 60

5. In an expansion joint forming mechanism including a precast plastic filler, of an edging unit comprising a metal edging bar, and pins secured therein to be driven into the plastic 65 filler for holding the edging bar on edge spaced inwardly away from the upper corners of the filler during the formation of the joint.

6. In a joint forming mechanism including a precast plastic filler for embedding between concrete road slabs, the combination of an edging 70 unit comprising a metal edging bar including tapered pins projecting therefrom to be driven into the plastic filler for holding the edging bar in position on edge and spaced inwardly away from the top corner edges of the filler to facil- 75

tate edging of the upper corners of the concrete slabs formed to overhang the top of the plastic filler by the depositing of concrete on portions of the top and on opposite sides of the plastic filler and the edging bar supported thereon.

5 7. A joint forming mechanism for concrete roads and the like, said mechanism comprising a base, a precast filler supported thereon, a metal edging bar seated on edge upon the precast filler, and pins secured to the edging bar and projecting into the precast filler for holding the edging bar in position with the sides thereof spaced inwardly away from the top corner edges of the filler.

15 8. The combination with a precast plastic filler for a road joint, of an edging bar of less thickness than the filler and supported on edge thereon, and pins forming a part of the edging bar and driven into the plastic filler for holding the bar in place leaving parts of the top surface of the filler exposed on opposite sides of the bar.

20 9. An expansion joint brace mechanism comprising a channel cap, a plurality of brackets secured to one side thereof, stop members secured 25 to said brackets, legs on said brackets for supporting the same in position, and removable stake members engaged with the brackets for releasably securing the joint holder in place.

25 10. An expansion joint holder comprising a cap, apertured brackets secured to one side of the cap, stop members secured to the brackets, legs on the bottoms of the brackets, and stake members projecting through the brackets and including handles for the removal of the stakes to permit 30 removal of the joint holder from concrete poured on opposite sides of the joint.

35 11. The combination with an expansion joint forming mechanism for embedding between concrete road slabs, of a joint holder for said mechanism including a channel cap, apertured brackets secured to the cap, legs for bracing the brackets in position, stakes releasably projecting through the apertured brackets, and handles projecting from the upper portions of the stakes 40 to facilitate removal of the stakes from the brackets and also serving to prevent the stakes from being driven completely through the brackets.

45 12. The combination with a precast plastic expansion joint filler for embedding in concrete for the formation of a joint between concrete road slabs, of a narrow steel edging bar including tapered pins to be driven into the precast filler to hold the edging bar in position, and a joint 50 holder for bracing the precast filler in position during the pouring of concrete and comprising a channel shaped cap for seating upon the top of the precast filler to enclose the steel edging bar, apertured brackets secured to one side of the cap, 55 stop members on the bottoms of the brackets for engaging against one side of the plastic filler to brace the same, supporting legs formed on the bottoms of the brackets, stakes projecting through the apertured brackets adapted to be 60 driven into a road subgrade to secure the joint 65 holder in place for bracing the cap and the precast filler in place during the pouring of concrete, and arms projecting from the stakes above the brackets for removing the stakes after the 70 completion of the joint and also serving to prevent the stakes from being driven through the apertured brackets.

75 13. In an expansion joint forming mechanism including a precast plastic filler, of an apertured crosshead plate supported on top of the filler, a

steel edging bar including pins projecting from the bottom thereof to be driven through the plate and into the plastic filler for holding the edging bar and plate in position during the formation of a joint.

5 14. The combination with a precast plastic expansion joint filler for embedding in concrete for the formation of a joint between concrete road slabs, of an apertured metal plate means seated upon the top of the filler, and a steel edging bar seated on the plate means and having pins projecting through the plate means and into the precast filler.

10 15. The combination with a precast plastic expansion joint filler for embedding in concrete for the formation of a joint between concrete road slabs, of an apertured metal plate crosshead seated upon the top of the filler and projecting beyond the sides thereof, a steel edging bar seated upon the apertured crosshead, and wedge pins 15 projecting from the edging bar and projecting through apertures in the crosshead to engage in the precast filler.

20 16. The combination with a precast plastic expansion joint filler for embedding in concrete for the formation of a joint between concrete road slabs, of an apertured metal plate crosshead seated upon the top of the filler and projecting beyond the sides thereof, a steel edging bar seated upon the apertured crosshead, wedge pins 25 projecting from the edging bar and projecting through apertures in the crosshead to engage in the precast filler, a cap engaged over the edging bar and seated on the crosshead and brace members connected with the cap for temporarily holding the same in position during the pouring of concrete for the formation of the joint.

25 17. The combination with a precast plastic expansion joint filler for embedding in concrete for the formation of a joint between concrete road slabs, of an apertured metal crosshead plate seated upon the filler and projecting beyond the sides thereof, a precast plastic bar seated on the plate, a steel edging bar supported upon the precast plastic bar, and wedge pins secured in the steel edging bar and projecting into the plastic bar to releasably hold the steel edging bar in position.

30 18. The combination with a precast plastic expansion joint filler for embedding in concrete for the formation of a joint between concrete road slabs, of an apertured metal crosshead plate seated upon the filler and projecting beyond the sides thereof, a precast plastic bar seated on the plate, a steel edging bar supported upon the precast plastic bar, wedge pins secured in the steel edging bar and projecting into the plastic bar to releasably hold the steel edging bar in position, a cap seated over the edging bar and resting on the precast plastic bar, brace members secured 35 to one side of the cap, and removable stakes for engaging the brace members to hold the same in position during the pouring of concrete for the formation of the joint.

35 19. The combination with a precast plastic expansion joint filler for embedding in concrete for the formation of a joint between concrete road slabs, of a pair of apertured overlapping crosshead plates seated upon the filler, an edging bar seated on the crosshead plates, and wedge pins 40 secured in the edging bar and projecting through the apertured overlapping crosshead plates into the plastic filler.

45 20. The combination of a precast plastic expansion joint filler for embedding in concrete for 45

the formation of a joint between concrete road slabs, of a metal crosshead seated on the filler and projecting beyond the sides thereof to be embedded in the road slabs, and edging means seated on the crosshead including means for projecting through the crosshead and into the plastic filler.

21. The combination with a precast plastic expansion joint filler for embedding in concrete for

the formation of a joint between concrete road slabs, of a plurality of apertured crosshead plates seated upon the filler and including flanges which project downwardly into the filler, an edging bar seated on the crosshead plates, and wedge members secured in the edging bar and projecting downwardly between the flanges of the crosshead plates into the plastic filler.

ROBERT R. ROBERTSON.
